2 SHEETS-SHEET 2.

UNITED STATES PATENT OFFICE.

JAMES L. BUTLER, OF ALLIANCE, OHIO.

ANNEALING-FURNACE.

979,425.

Specification of Letters Patent. Patented Dec. 27, 1910.

Application filed August 25, 1909. Serial No. 514,473.

To all whom it may concern:

Be it known that I, JAMES L. BUTLER, a citizen of the United States, residing at Alliance, in the county of Stark and State of Ohio, have invented certain new and useful Improvements in Annealing-Furnaces, of which the following is a specification.

In annealing furnaces in which the articles to be annealed are introduced and withdrawn from the oven on cars or trucks, trouble has heretofore been experienced owing to the warping, twisting, distorting, and expanding and contracting of the car or truck, due to the great heat, especially in the annealing of flat plates. With such articles it is particularly important that the car shall remain perfectly flat, even though subjected to considerable variations in temperature, and to effect this result I provide the car with balls on which to roll, and so construct the device that the expansion and contraction does not interfere with the proper action of the anti-friction balls, and does not result in detrimental distortion of the car or the plates which it supports and carries.

In order that a full understanding of this invention may be had, I have illustrated a desirable embodiment of the same in the accompanying drawings which form a part of this specification, and to which reference should be made, like reference characters referring to the same parts throughout the various views of these drawings.

Figure 1 is a cross section of an annealing oven equipped with my improved form of car or carrier; Fig. 2 is a plan view of the car on a reduced scale, the firebrick covering of the same being omitted; Fig. 3 is an end view of one of the two companion parts or sections of which the car or carrier is composed; Fig. 4 is a longitudinal section through the annealing oven or furnace; Fig. 5 is a plan view of one of the track sections for the anti-friction balls; and Fig. 6 is an end view of such section, one of the balls being indicated in dotted lines.

Reference being had to these drawings, it will be noticed that therein I have illustrated an annealing oven or furnace 10 having an arched top 11, a flat floor or bottom wall 12, and side walls 13 and 14. Inasmuch as this oven may be of any suitable or ordinary construction for the application of

heat to its interior, further description of the oven proper is deemed unnecessary.

On the floor or bottom wall 12, which may be made of any desired heat-resisting material, I mount three grooved parallel tracks 15, 16 and 17, the parallel top grooves of which are substantially semi-cylindrical. Each track is made of a plurality of aligned, associated sections 18 (Figs. 4 and 5) having apertured lateral ears 19 for the attachment of the same, by bolts or otherwise, to a plurality of cross plates 20 sunk in the top face of the floor or bottom wall 12. In order to assist in the proper assembly of such sections and their maintenance in the proper alignment, one end of each section 18 has a V-shaped projection 21, while its other end is supplied with a correspondingly-shaped cavity 22 adapted to receive the projection of the adjacent companion section. Each of these grooved trackways accommodates a plurality of anti-friction, metal, spaced, spherical balls 23 in the same horizontal plane and adapted and intended to support the car or carrier 24, which is inserted into and withdrawn from the oven 10. This metallic car 24 is made in two sections 25 and 26, which are alike and may be produced from the same pattern, being united together substantially medially and transversely of the car, as is indicated in Figs. 2 and 4. Each car section is provided on its top face with a pair of rectangular depressions or cavities 27 and 28 adapted to receive and accommodate the outwardly-extended ears or projections 29 and 30 of the companion car-section, such ears or projections being riveted to the other part of the car, as is clearly illustrated. By the employment of a construction of this kind, I am enabled to build a car of considerable size by the use of a pattern and castings of much less dimensions. The two longitudinal edges of each car-section are supplied with upstanding, parallel, marginal flanges 31, and at each end the car is equipped with a transverse trough 32, the top edge of which is in the same plane with the corresponding edges of the flanges 31. Depending from the bottom surface of this car and extended longitudinally thereof near its outer edges are two smaller flanges 33 and 34, the functions of which will be indicated hereinafter. Centrally and longitudinally

disposed on the under or bottom surface of this car is a grooved trackway 35 adapted to receive the top portions of the plurality of balls 23 in the center track 16. The bottom surface of this car is also supplied with two flat, horizontal track surfaces 36 adapted to rest on the tops of the balls 23 of the two outer companion trackways 15 and 17.

On the top face of the car I provide a layer 37 of insulating material, on which I superpose a body of firebrick 38 held on the car and maintained in proper position by the flanges described above. In order to limit the amount of heat which may reach the balls and trackways, I mount bent plates 39 on the inner faces of the side walls 13 and 14 so as to form longitudinal channels for the accommodation of the two bodies of sand or similar material 40, into which the flanges 33 and 34 on the bottom of the car reach so as to form a sort of sand seal between the top of the car and the parts and elements below the same. In order also that the ends of the oven may be suitably closed, the two transverse channels 32 at the ends of the car are likewise supplied with sand 41, into which the lower edges of the doors 42 are dropped so as to securely seal the oven, will be readily understood.

The operation of this appliance takes place practically in the following manner: The doors 42 having been lifted and the car 24 having been rolled out of the oven, it is loaded with the articles to be annealed, such, for example, as flat plates. It is then rolled into the oven, which operation is readily and easily accomplished owing to the facility with which the balls 23 travel in their respective tracks, transverse movement of the car being prevented owing to the coöperation of the upper, central, grooved track 35 with its row of balls. As the car travels into the furnace or oven, the flanges 33 and 34 engage the two bodies of sand 40 in the side channels, forming the seals hereinabove mentioned. The end doors are then pulled down or dropped to the positions indicated in Fig. 4, their bottom edges entering the bodies of sand 41, also forming seals, so that the load of the car may be subjected the desired length of time to the heat in the oven. The space below the car, occupied by the tracks and balls, is open to the atmosphere at both ends, as is shown in Fig. 4, so as to reduce the heat to which the parts occupied by this compartment are subjected. Owing to the fact that the trackways 36 on the bottom of the car are flat and are free to travel laterally or transversely outwardly under the expansion action of the heat to which the car and its load are subjected, such expansion may occur without causing any distortion or warping of the car-body, with its consequent and resulting buckling of the plates carried

by the car, and when the car cools, owing to this permissible lateral travel or movement between the outer rows of balls and the flat tracks 36, the car may assume its original condition without distortion, twisting or the like. In other words, by this invention I have provided an effective means for caring for the expansion and contraction of the car, at the same time maintaining the surface of the same in a practically undistorted or untwisted plane so that the flat plates or other parts carried thereby will in no way be detrimentally affected by distortion of the car.

Whereas I have herein indicated, both by description and illustration, one particular style or form of a car embodying my invention, I wish to have it understood, however, that the invention is susceptible of a variety of embodiments and that the structural features of the appliance of this application may be modified within comparatively wide limits without departure from the heart of the invention.

I claim:

1. The combination of an annealing furnace having a plurality of tracks on the floor of the annealing chamber of the furnace, of a car having track members corresponding to the tracks of the furnace, and anti-friction balls interposed between corresponding track members, the track members of the furnace being grooved to receive the balls, at least one of the track members of the car being grooved to fit the balls and prevent side movement of the car, the remaining track members of the car having bearing faces exceeding in width the width of the bearing upon the balls to permit expansion and contraction of the car bottom without binding upon the balls.

2. The combination of an annealing furnace having a plurality of grooved track members on the floor of the annealing chamber, of a car having track members corresponding to the track members of the furnace, and anti-friction balls interposed between the track members of the furnace and the car, one of the track members of the car being located at the longitudinal center of its bottom and grooved to fit the adjacent balls, the other track members of the car having flat bearing surfaces.

3. The combination of an annealing furnace, a car, and sets of anti-friction devices supporting the car upon the floor of the annealing chamber of the furnace, said devices being held against bodily movement transversely of the car, and the car having a track member grooved to fit one set of anti-friction devices to prevent lateral movement of the car.

4. The combination of an annealing furnace having a plurality of grooved track members on the floor of the annealing cham-

ber, balls adapted to travel in the grooves of such tracks, a car supported by and adapted to roll on said balls, and tracks carried by the underside of the car and bearing on the balls of the respective tracks on the floor of the furnace, one or more of the car tracks being flat to permit expansion and contraction of the car without interfering with its operation, the other car tracks being grooved to partially receive the balls 10 and maintain the car in proper relation with such balls, substantially as described.

JAMES L. BUTLER.
